UNITED STATES PATENT OFFICE.

EDWARD GEORGE MORLEY, OF MALVERN, MELBOURNE, VICTORIA, AUSTRALIA.

GOLF-CLUB ATTACHMENT.

1,075,054.

Specification of Letters Patent.

Patented Oct. 7, 1913.

Application filed February 10, 1913. Serial No. 747,413.

To all whom it may concern:

Be it known that I, EDWARD GEORGE MORLEY, merchant, a subject of the King of Great Britain and Ireland, residing at 5 Kooyong Road, in the town of Malvern, a suburb of the city of Melbourne, in the county of Bourke, State of Victoria, Commonwealth of Australia, have invented a new and useful Improvement in Golf-Club Attachments, of which the following is a specification.

This invention relates to golf clubs and like devices which, in use, it is desirable to retain firmly in the hand.

15 Hitherto the shaft of a golf stick or club has sometimes had attached thereto devices of various construction to assist a player in grasping the club and in perfecting his aim. These devices have sometimes consisted of resilient sleeves and the like so that the shaft may be grasped in such a manner that better control is obtained over it and more of the player's attention may be given to striking the ball.

25 The object of this invention is to provide a simple, light, strong and durable combination finger stop and grip which can be easily applied to any golf club or similar implements. In use it does not harass 30 either the fingers or hands of the player, may readily accustom itself to different grips and enables a player to correctly position the shaft of the club in the hand in an instant without any doubt. In addition the 35 stick or club cannot slip in the hand at a critical moment.

With the invention the player knows by 40 the feel as to whether the position he has acquired of the shaft of the club is a correct one both longitudinally and circumferentially. In order that the aim may be correct the club shaft must occupy a certain pre-determined position in the hands, and this is facilitated by the invention thereby assuring results which are often unobtainable otherwise.

45 Referring to the drawings which form a part of this specification: Figure 1 is a perspective view of one form of finger stop and grip. Fig. 2 is a side view showing one method of securing the stop and grip to portion of the handle of a stick or club. Fig. 3 is a sectional view showing another method of securing the stop and grip to 50 portion of the handle of a stick or club. Fig. 4 is a perspective view of one form of

adjusting device. Fig. 5 is a perspective view of another form of adjusting device. Fig. 6 is a view showing portion of the stop and grip secured to portion of the handle of a stick or club, by an adjusting device. Fig. 7 is a view of another form of stop and grip divided longitudinally and embracing portion of the handle of a stick or club. Fig. 8 is a view of Fig. 7 looking in the direction of the arrow. Fig. 9 is a view of Fig. 8 looking in the direction of the arrow. Fig. 10 is a plan of the stop and grip seen in Figs. 7, 8 and 9. Fig. 11 is a view of a modification of the stop and grip seen in Fig. 7 retained to portion of the handle of a stick or club by holding devices of the kind seen in Fig. 5. Fig. 12 is a part sectional perspective view of a divided adjusting tapered sleeve. Fig. 13 is a view showing a stop and grip of the character seen in Figs. 7 to 11 but in one piece and retained to portion of a stick or handle by the sleeve seen in Fig. 12. Fig. 14 is a sectional view of a modified form of stop and grip of the kind seen in Figs. 7 to 10 and having a multiplicity of finger separators. The retention screws are shown diametrically opposite the finger separators for convenience of illustration. Fig. 15 is a view, on a reduced scale, showing the use of the stop and grip seen in Figs. 1 to 3 in conjunction with the stop and grip seen in Figs. 7 to 10.

The invention includes the handle 2 of a golf stick or club or similar instrument. This is of tapered or coned conformation. Wound around or upon the upper end or handle of the stick or club is a leather or other thong 3. This is usual practice in the manufacture of such devices.

The invention consists in an attachment or finger stop and grip. Any suitable flexible material or materials may be employed in its manufacture. If more than one material be used they may be united in any well known way. The said attachment (Figs. 1 to 3) has a longitudinal semi-circular or hollow foundation surface 4. The length of this depends upon conditions. In width it may be little less than the width of the shaft at that portion of its length where the attachment is secured. At the upper end of the said attachment is an upper flange 5 the thickness of which will vary with circumstances. Its height is also of such a character as to suit the individual taste of the

player. At the lower end of the said attachment is a lower flange 6. The thickness of this may vary as may also its height.

Extending downwardly from the lower portion of the outside of the upper flange 5 is an outwardly inclined extension 7. The length of this as also the inclination thereof may vary with the club being used. The lower extremity of the said extension may be in alignment with the lower end of the lower flange 6 or it may extend beyond the same, or not extend to that distance. Between the lower extremity of the said extension 7 and the outside of the lower flange 6 is situated a transverse finger gullet 8. The inside of this is formed by the outside of the said lower flange 6 and the outside is formed by the inside area of the lower portion of the said extension 7. The root or 20 crown 9 of the said gullet is formed within or by the main portion of the said extension. The contour of the said gullet may vary to suit the fancy of the player. Through the body of the said finger stop 25 and grip and transversely situated with regard thereto and parallel with the top or crown of the gullet 8 are one or more holes 10. Through the hole or holes 10 is passed a joining wire or cord 11 or other flexible 30 material whereby the said attachment is attached to the exterior of the shaft. The attachment is so positioned that the outer portion and right side of the little finger of the hand beds therein comfortably. Instead 35 of the said attachment being secured by a binding wire 11 or the like it may be secured by an agglutinant of any suitable character. Or it may be secured by screws 12, or by nails; or it may be bound by the 40 thong 3 with which the handle of the shaft is enveloped.

Instead of securing the finger stop and grip to the handle in a fixed position as described, it may be adjustably secured there- 45 to. A band 13 (Fig. 4) may then envelop the stick 2 and each flange of the finger stop and grip. Passing through the band 13 is a retention screw. This consists of a free head 14 mounted loosely upon the inner end 50 of a threaded shank 15. Secured to the outer end of the shank 15 is a winged head 16. The diameter, thickness and width of the band may vary. It may also be composed of spring, elastic or flexible material.

55 Instead of employing a band to provide adjustable attaching means a strap 17 (Fig. 5) may be used having flanges or lugs 18. Passing through the flanges 18 is a clamping or holding screw 19.

60 Instead of the attachment before described a finger stop and grip may be used which encircles or partially encircles the shaft 2. This finger stop and grip (Figs. 7 to 10) consists of a body divided into a first section 65 20 and a second section 21. Each section is

provided with a semi-circular or hollow foundation surface. Passing through or formed in each section are one or more screw holes accommodating screws 22 by which the sections are secured to the shaft 2. Integral 70 with the body of the finger stop and grip is an overhanging finger separator 23 provided with an overhanging edge 24. The length and thickness of the separator may vary. Preferably it is thicker at its inner 75 portion than the outer edge.

The upper surface of the separator forms an upper finger bed having a first finger joint portion 25, a second finger joint portion 26 and a third finger joint portion 27. The lower surface of the separator 23 forms a lower finger bed having a first finger joint portion 28, a second finger joint portion 29 and a third finger joint portion 30. Formed in or upon the surface of the first section 20 is a thumb bed 31 having an inclined surface of such conformation that it will comfortably accommodate the thumb of the player. The attachment or finger stop and grip may be formed of any suitable material. It may be resilient or it may be rigid.

Instead of securing the sections 20 and 21 by means of screws 22 or the like either the band 13 or the strap 17 may be used for that purpose. To facilitate such attachment each section is provided with an upper extension 32 and a lower extension 33 the said extensions being of such a length that the bands or straps are free of and are not grasped by the hand. Or instead of the attachment being formed in two sections it (Fig. 13) may be formed in one piece. A divided adjusting sleeve (Figs. 12 and 13) may then be used to secure and adjust the stop and grip upon the golf stick or club. The divided sleeve is preferably formed of metal and comprises a first half 34 and a second half 35 each having an upper end 36 and a lower end 37. The upper end 36 of each half is of greater thickness than the lower end thereby providing a tapered wall to each said half of the sleeve. Expressed inwardly from each half of the sleeve are integral tongues 38. Or instead of forming the stop and grip seen in Figs. 7 to 10 with 110 but one finger separator a series of superimposed separators (Fig. 14) may be used. The body of the finger stop and grip is then 115 tubular and may be formed in one piece or divided into sections. It may be secured to the shaft of the stick or club by either of the adjusting devices seen in Figs. 4 and 5. Or it may be screwed thereto, or be attached by a binding wire, cord or the like. As shown in Fig. 15 the finger stops and grips before described may be used in conjunction, that illustrated in Figs. 1 to 3 being disposed above that seen in Figs. 7 to 10.

The modified stop and grip may be secured to the shaft of the stick or club by 120

means of wires or cords 11 bound around the said shaft and around flanges of the attachment. Or the attachment may be secured by the thong 3 which is bound around the shaft. 5 Or the said stop and grip may be secured by screws 22 or by a band such as 13 or a strap such as 17.

With this invention a full, effective and complete control of the golf club is secured 10 by the player as he can grasp the shaft of the club and instinctively feel the position that the shaft occupies in his hands. No attention need be given to the position the shaft occupies in the hand and more attention 15 can therefore be directed to the ball and to the hole to which it is to be directed. In action the club cannot creep or move by accident. In using the stop and grip seen in Fig. 1 the right side, the inside and the out- 20 side of the little finger of the hand are accommodated beneath the extension 7 and in the gullet 8. The inside of the finger grips the outer surface of the lower flange 6. As the club is swung it is impossible for the said 25 club to slide in the hand as the attachment forms a stop against which the finger bears. The position of the attachment upon the club rendered it possible for the player to grasp the stick always in the same place.

30 In using the stop and grip seen in Figs. 7 to 10 the right hand side of the first finger of the hand bears or repose in the lower finger bed formed by the lower face of the separator 23. The inside of the finger 35 grasps the body of the stop and grip. The left hand side of the second finger of the hand rests upon the upper finger bed formed by the upper surface of the separator 23. The separator is thus interposed between 40 the fingers. The thumb of the hand repose in or upon the thumb bed 31. By means of this attachment not only is the shaft prevented from moving in any way in the hand but the club is always grasped positively in 45 the same manner. By using the stop and grip seen in Figs. 1 to 3 in conjunction with that seen in Figs. 7 to 10 the club or like device is always grasped in the same manner and cannot slip when swung.

50 Having now described my invention, what I claim as new and desire to secure by Letters Patent is:—

1. Improvements relating to golf club attachments, consisting in the combination of 55 a finger stop and grip provided with a semi-circular longitudinal foundation surface and having an upper flange and a lower flange, a downwardly inclined extension projecting from said stop and grip between said flanges and forming a finger gullet, and means for fixedly securing the stop and grip to the golf club.

2. Improvements relating to golf club attachments, consisting in the combination of 60 a finger stop and grip provided with a semi-

circular longitudinal foundation surface and having an upper flange and a lower flange, a downwardly inclined extension projecting from said stop and grip between said flanges and forming a finger gullet, and 70 means for adjustably securing the stop and grip to the golf club.

3. Improvements relating to golf club attachments, consisting in the combination of 75 a stop and grip having longitudinal semi-circular foundation surface, an upper flange and a lower flange to said stop and grip, an inclined extension projecting from said stop and grip between said flanges and forming a finger gullet, a band securing said stop and grip to the golf club, and a reten- 80 tion screw passing through said band.

4. Improvements relating to golf club attachments, consisting of the combination of 85 a finger stop and grip provided with a lon- gitudinal semi-circular foundation surface and having an upper flange and a lower flange, a downwardly inclined extension projecting from said stop and grip between said flanges and forming a finger gullet, a strap 90 securing said stop and grip to the golf club, lugs projecting from said strap, and a hold- ing screw passing through said lugs.

5. Improvements relating to golf club attachments, consisting of the combination of 95 a divided finger stop and grip each section being provided with a semi-circular founda- tion surface and having an overhanging fin- ger separator provided with upper and lower finger beds, and means for securing 100 the stop and grip to the golf club.

6. Improvements relating to golf club attachments, consisting of a finger stop and grip having a first section and a second sec- 105 tion each provided with a semi-circular foundation surface, an overhanging finger separator projecting from said stop and grip and forming an upper finger bed and a lower finger bed, each bed having a first finger joint portion, a second finger joint 110 portion and a third finger joint portion, and a thumb bed formed in said grip.

7. Improvements relating to golf club attachments, consisting of the combination of 115 a finger stop and grip provided with a first section and a second section, an upper ex- tension and a lower extension to each sec- tion, an overhanging finger separator pro- 120 jecting from said stop and grip and provid- ing an upper finger bed and a lower finger bed, a thumb bed formed in said grip and an adjusting device encircling the exten- sions and securing the stop and grip to the golf club.

8. Improvements relating to golf club at- 125 tachments consisting of the combination of a finger stop and grip provided with a first section and a second section, an upper ex- 130 tension and a lower extension to each sec- tion, an overhanging finger separator pro-

jecting from said stop and grip and providing an upper finger bed and a lower finger bed, a thumb bed formed in said grip, and adjusting devices for securing the stop and grip to the golf club by encircling the extensions, each device comprising a band carrying a retention screw.

9. Improvements relating to golf club attachments, consisting of the combination of 10 a finger stop and grip provided with a first section and a second section, an upper extension and a lower extension to each section, an overhanging finger separator projecting from said stop and grip and providing an 15 upper finger bed and a lower finger bed, a thumb bed formed in said grip, and adjusting devices for securing the stop and grip to the golf club by encircling the extensions, each device comprising a strap having lugs, 20 and a holding screw passing through the lugs.

10. Improvements relating to golf club attachments consisting in the combination of a finger stop and grip having an over- 25 hanging finger separator forming an upper finger bed and a lower finger bed, a thumb

bed formed in said stop and grip, a divided sleeve between said stop and grip and the golf club, a first half and a second half to said sleeve, the walls to each half being tapered, and tongues projecting inwardly from each said half.

11. Improvements relating to golf club attachments, consisting in the combination with a golf club or stick of a finger stop and 30 grip, an overhanging finger separator projecting from said stop and grip and forming an upper finger bed and a lower finger bed, a thumb bed formed in said stop and grip, a finger stop and grip above the protruding separators and consisting of an upper flange and a lower flange, and a downwardly inclined extension projecting from said grip between said flanges and forming a transverse finger gullet.

In testimony whereof I have signed my name to this specification in the presence of two subscribing witnesses.

EDWARD GEORGE MORLEY.
